W^m. B. Madelus, of Cincinnati, Ohio.

Letters Patent No. 11447-Dated Feb. 16th 1864.

Design for Labelling Barrels.

The schedule referred to in these Letters Patent and making part of the same.

To all whom it may concern:

Be it known that I, William B. Madelus, of Cincinnati, in the County of Hamilton, and State of Ohio, have invented a new Ornamental Design for Label for Barrels; and I do hereby declare the same to be fully represented in the accompanying specimen, making part of this specification.

What I claim as new and desire to secure by Letters Patent is,

The Design herein represented for a Label for Barrels.

In testimony of which Invention I have countersigned my hand.
